Lewis H. Gustafson and Gordon S. Swift, Northampton, Mass., assignors to Pro-phy-lac-tic Brush Company, Northampton, Mass., a corporation of Delaware

Application January 22, 1941, Serial No. 98,277

Term of patent 14 years

To all whom it may concern:

Be it known that we, Lewis H. Gustafson and Gordon S. Swift, citizens of the United States of America and residents of Northampton, in the county of Hampshire, Commonwealth of Massachusetts, have invented a new, original, and ornamental Design for Hairbrushes, of which the following is a specification, reference being had to the accompanying drawing, forming part thereof.

In the drawing:

Fig. 1 is a face view of a hairbrush showing our new design.

Fig. 2 is a side elevation.

Fig. 3 is a back view.

Figs. 4 and 5 are end elevations, looking from the head end and handle end, respectively.

We claim:

The ornamental design for a hairbrush, substantially as shown.

LEWIS H. GUSTAFSON.
GORDON S. SWIFT.
